UNITED STATES PATENT OFFICE.

FRED CHARLES MAIRSON, OF CHICAGO, ILLINOIS.

ADJUSTABLE ROLLER-TRACK.

1,358,170.

Specification of Letters Patent. Patented Nov. 9, 1920.

Application filed May 6, 1919. Serial No. 295,224.

To all whom it may concern:

Be it known that I, FRED CHARLES MAIRSON, a citizen of the United States, residing at Chicago, in the county of Cook and State 5 of Illinois, having invented new and useful Improvements in Adjustable Roller-Tracks, of which the following is a full, clear, concise, and exact description, reference being had to the accompanying drawing, forming 10 part of this specification.

My invention pertains to adjustable tracks, and especially relates to adjustable roller tracks for the ink rollers of printing presses, particularly platen presses of the 15 Gordon type.

In the ordinary platen printing press, inking rollers are reciprocated between an ink disk and the type at every cycle of the press, thereby conveying ink from the disk and 20 spreading it over the type in the form. These inking rollers are provided with rolls which run upon tracks formed by the edges of the side arms which support the disk. It has heretofore been proposed to provide adjustable tracks to take the place, in operation, of the stationary tracks above referred to, thereby to permit the ink rollers to be brought closer to the type, or be moved farther away from it, in accordance with the 25 nature of the job being printed, and to permit of compensation for wear of the tracks or of the rolls of the inking rollers, and for shrinkage or expansion of the rollers due to climatic changes or the like. It is the 30 principal object of my invention to improve upon such adjustable roller tracks particularly with regard to the means for effecting the adjustment. It is another object of my invention to provide such an adjustable 35 roller track which will require a minimum amount of work upon the press in order to permit of its attachment thereto.

As an example of one form in which my invention may be embodied, I have described 40 in the following specification, and shown in the accompanying drawing, an adjustable roller track constructed in accordance with my invention, as applied to a printing press of the Gordon type.

50 In the drawing:

Figure 1 is a side elevation of a portion of a Gordon press, having an adjustable roller track constructed in accordance with my invention applied thereto;

Fig. 2 is an enlarged view of the top of 55 the track; and

Fig. 3 is a section on the line 3—3 of Fig. 2, looking in the direction of the arrows.

In the drawing, 10 indicates one of the 60 side frames of the press, and 11 the ink disk. Traveling between the ink disk and the form carried between the frames 10 are the inking rollers supported in the carriages 12. These carriages have rollers 13 which, 65 in a press not provided with auxiliary tracks, run upon the edges of the frames 10.

In carrying out my invention, I provide track members mounted on the outside faces of the frames 10. Each of these track members includes a front portion 14, the outer edge of which is shaped in conformity with the shape of the tracking edge of the frame 10 and an inner portion 15 of a reduced thickness. In practice, a track member is 70 placed on each side of the press, being mounted upon the outer faces of the frames 10. This mounting is so effected as to permit of an inward and outward adjustment with respect to the plane of the type surface. To 75 permit of this adjustment I provide a device at each end of each roller track. Each of these devices comprises an eccentric 16 mounted in the track member at the side thereof next the adjacent frame 10. The 80 eccentric 16 is formed with a head 17 of enlarged diameter, which rests upon a shoulder 18 formed in the track member. A cap screw 20 passes through the eccentric 16 and head 17 and is tapped into the frame 10. 85 The head 17 is provided with notches 21 for receiving a spanner wrench.

In effecting an adjustment of the tracks, the cap screw 20 of one of the tracks is first loosened, thereby permitting the eccentrics 90 16 to be rotated by means of their heads 17. By applying a spanner wrench to the heads 17, the eccentrics 16 are then turned so as to give the required adjustment of the track member with respect to the plane of the face 100 of the type. Upon again tightening the cap-screws 20, the heads 17 firmly clamp the track member against the frame, and prevent its movement from the adjusted position. It will be noted that the adjustment 105 may be made very easily and quickly, and with great fineness. Attention is further drawn to the fact that the adjusting means

is of an exceedingly simple character and cannot possibly be put out of order in the course of ordinary use. A further advantage lies in the fact that the application 5 of my improved adjustable track to a press requires nothing more than the drilling and tapping of the four holes for the cap screws 20, and that such nicety of positioning of these holes as would necessitate highly skill- 10 ed workmanship is not required.

Having thus fully described my invention, what I claim as new and desire to secure by Letters Patent, is:

1. In combination, a printing press frame, 15 adjustable roller rails mounted each side of the frame, a pair of eccentric adjusting elements for each rail, one disposed each side of the center of each rail, and means for locking each eccentric and the roller 20 rails to the frame.

2. In combination, a printing press frame, formed with alined threaded openings, adjustable roller rails mounted each side the 25 frame, each rail having openings one each side the center, said openings being ec-

centric to the openings in the frame, eccentrics mounted in the eccentric openings, and screws extending through the eccentrics and into the threaded opening in the frame to lock the eccentrics and the rails to 30 the printing frame.

3. In combination, a printing press frame, formed near the top and bottom with alined threaded openings, roller rails at each side the frame, each roller rail having openings 35 near the top and bottom, eccentric to and adjacent the threaded openings, flanged eccentrics mounted in the openings in the rails, the flanges of the eccentrics engaging 40 the outer surfaces of the rails, and threaded elements passing through the eccentrics and into the threaded openings to lock the eccentrics and rails in adjusted position.

In witness whereof I have hereunto subscribed my name in the presence of a witness.

FRED CHARLES MAIRSON.

Witness:

THEO R. FOSTER.
